INVENTOR

A. G. Vermilya

UNITED STATES PATENT OFFICE.

ALLEN G. N. VERMILYA, OF NEW YORK, N. Y., ASSIGNOR TO THE CARY MANUFACTURING COMPANY, OF SAME PLACE.

DESIGN FOR A REEL-FRAME.

SPECIFICATION forming part of Design No. 30,063, dated January 24, 1899.

Application filed September 12, 1898. Serial No. 690,809. Term of patent 14 years.

To all whom it may concern:

Be it known that I, ALLEN G. N. VERMILYA, a citizen of the United States, and a resident of New York, in the county of New

5 York and State of New York, have invented and produced a certain new and original Design for a Reel-Frame, of which the following is a specification, reference being had to the accompanying drawings, forming part of the 10 same, in which—

Figure 1 is a perspective view of my newly designed reel-frame, and Fig. 2 is a side elevation of the same.

The frame which I have designed consists, 15 primarily, of two arms f and f' , joined one to the other at or near the ends and extending parallel one with the other, but separated one from the other by a short space for the greater part of their lengths. At or near one end, the 20 two arms having been brought together, an extension is carried on beyond the line of the junction, and in such extension there is an

aperture. I have marked it h^2 . About midway between the ends, or rather between the places where the arms are brought together, 25 are axle-holes h h' .

The main features of the design are the two parallel connected arms extending parallel, but separated for most of their lengths, brought together at or near the ends, and provided with an apertured extension projecting beyond the point of junction and with axle-holes between the two places of junction, substantially as set forth.

What I claim as my invention, and desire to 35 secure by Letters Patent, is—

The design for a reel-frame substantially as shown and described.

Signed at New York, in the county of New York and State of New York.

ALLEN G. N. VERMILYA.
